The ornamental design for a display with graphic user interface, as shown and described.

DESCRIPTION

FIG. 1 is a front view of a display with graphic user interface showing the new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

The appearance of the image transitions sequentially between the images shown in FIGS. 1-8;

FIG. 9 is a front view of a another display with graphic user interface showing our new design;

FIG. 10 is the second image thereof;

FIG. 11 is the third image thereof;

FIG. 12 is the fourth image thereof;

FIG. 13 is the fifth image thereof;

FIG. 14 is the sixth image thereof;

FIG. 15 is the seventh image thereof;

The appearance of the image transitions sequentially between the images shown in FIGS. 9-15;

FIG. 16 is a front view of a another display with graphic user interface showing our new design;

FIG. 17 is the second image thereof;

FIG. 18 is the third image thereof;

FIG. 19 is the fourth image thereof;

FIG. 20 is the fifth image thereof; and,

FIG. 21 is the fifth image thereof.

The appearance of the image transitions sequentially between the images shown in FIGS. 16-21.

The broken line showing of the remainder of the display is for environmental purposes only and forms no part of the claimed design. The subject matter in this patent includes a process or period in which an image changes into another image. This process or period forms no part of the claimed design.
